UNITED STATES PATENT OFFICE

JOSEF GREINER, OF VIENNA, AUSTRIA, ASSIGNOR TO G. A. UNGAR AND ERIC BENJAMIN, BOTH OF NEW YORK, N. Y.

CAPSULE OF MICROPHONES

Application filed November 27, 1929, Serial No. 410,060, and in Austria November 29, 1928.

The microphone boxes hitherto used must be entirely removed and replaced, if they are damaged by the carbon particles having been burnt out, since the constituents of such microphone boxes could only be replaced in the factory by means of mechanical appliances.

Such replacement was expensive and complicated since a telephone subscriber cannot hold a stock of boxes owing to the relatively high cost of same.

This drawback is obviated by the present invention.

The improved microphone box comprises essentially two main portions and viz a metal casing and a microphone body or cartridge. The first remains always in position of mounting, whereas the latter may be easily removed and replaced. The metal casing which forms the container of the microphone body, consists essentially of two portions, namely an upper portion clamping fast the diaphragm and a lower portion having a spring which forces the microphone body to the diaphragm of the upper portion and holds it in position.

The second main portion, the microphone body or cartridge comprises a felt ring, which is closed by two current conducting sheets of metal or carbon, so that a cylindrical hollow space is formed for receiving the carbon particles. Such space may also be subdivided, for preventing the carbon particles from baking together.

Such microphone body is forced by a spring, to the diaphragm, and does not directly contact the same but a small cone which is fixed either on the diaphragm or on the microphone body itself in order to avoid every damping by the different materials which the microphone body and the diaphragm present. By obviating a rigid connection between the diaphragm and microphone body an excellent speaking effect is obtained.

The microphone body may be inserted, re-

moved and replaced in a very easy and ready manner, and this manipulation may be effected by non-experts.

In the drawings:

Figs. 1 and 2 show the microphone body. Fig. 3 is a cross section through the metal casing containing a microphone body. Fig. 4 shows the removable lower portions of the casing and Fig. 5 the upper portion of the casing.

M is the diaphragm, G the upper portion of the casing, R a ring which secures the diaphragm M to the casing G. P represents the microphone body which is pressed towards the diaphragm M by a spring F. S is a cup in which the microphone body is seated. V is the lower portion of the metal casing which is removably connected to the upper portion G thereof by means of a bayonet-joint. On said cup the spring F is seated so as to be insulated therefrom. K is a contact piece which conducts the current to the spring F and to the microphone body. Figs. 4 and 5 show by way of an example a bayonet-joint. The lugs r, r of the joint may be passed through the openings y, y of the casing, so that by revolving one of the portions of the casing in the direction of the arrow (Fig. 5) the lugs engage the marginal portion of the casing portion G so that the two portions of the casing are jointed.

Having fully described my invention, what I claim as new and desire to secure by Letters Patent is:

Microphone box comprising a casing and a microphone body, which is loosely inserted and may be removed and replaced, the casing consisting of two portions, a diaphragm provided at its center with a coneshaped projection being arranged on one of the said portions and a spring carried by the second portion, which spring serves for leading current to the microphone body and presses the latter slightly to the diaphragm, said second portion being arranged so that it may be

readily detached from the first named portion for the purpose of removing and replacing the microphone body the interchangeable microphone body consisting of a ring made up of felt or other resilient or elastic material, which ring is covered at both sides with a current conducting plate, so that a chamber is formed for receiving the microphonic particles.

10 In testimony whereof I affix my signature.
JOSEF GREINER.
